UNITED STATES PATENT OFFICE.

HENRY LEISER, OF CINCINNATI, OHIO.

GARMENT SAMPLE.

SPECIFICATION forming part of Letters Patent No. 287,760, dated February 15, 1881.

Application filed August 7, 1879.

To all whom it may concern:

Be it known that I, HENRY LEISER, of Cincinnati, in the county of Hamilton and State of Ohio, have invented a Sample Profile for 5 Indicating the Cut and Style of a Garment, and for Advertising Purposes, of which the following is a specification.

The object of the invention is to save weight and bulk for traveling salesmen or drummers 10 (who have heretofore carried with them entire garments or garments made up of various cloths) by furnishing them with finished samples or fragments of garments, said samples or fragments being made in such a manner as 15 to answer every purpose of an entire garment.

My improvement is a new article of manufacture for indicating the cut and style of a garment, and is used for advertising purposes, 20 consisting of a flat finished sample profile having a curved recess or cut-away for the passage of the arm, as hereinafter described.

In order that the invention may be fully understood, I will proceed to describe it with reference to the accompanying drawings, in 25 which—

Figure 1 is a front view of my improved profile sample of a garment. Fig. 2 is a rear view.

The drawings represent a profile of a coat, 30 indicating the cut and style of the whole garment.

a is a curved recess or cut-away for inserting the arm, leaving shoulder and side projections, *b c*, to lie over and under the arm, which 35 is received edgewise of the profile, the parts *b c* being disconnected, as shown at *d*.

It will be observed that the cut or style is clearly shown, also the form of buttons, the position of the pockets, the stitching, and the 40 lining, so that the purchaser is shown a sufficiently large portion or sample of the garment for him to tell precisely what the goods will be when delivered, if in keeping with the sample; or the purchaser can by the sample indicate any desired changes. The salesman, in 45 exhibiting a sample such as is represented in

the drawings, merely places it on his side or on the dummy, with his or the dummy's arm passed sidewise into the recess made therefor. The purchaser sees immediately the front of 50 the coat, including the waist, skirt, and half the collar; also the pockets and buttons belonging to that part, and by turning back a portion will readily see the style of and quality of lining. This is considerably less than half a 55 coat, and yet fully represents what a whole coat would be. It saves at least three-fourths of the material heretofore used for the purpose, is easily packed because flat, and costs less in shipping charges. As it is flat, it is not liable 60 to be crumpled and put out of shape or get creased, and consequently saves re-ironing and re-pressing. A great saving of time is effected in exhibiting this sample, as an entire garment does not have to be put on or taken off. As 65 not more than one specimen of cloth is put into the sample, it can be utilized in making up a whole garment.

It will be observed that the arm does not have to be passed through an armhole, but is 70 received through the entrance *d*, thus preventing the necessary wear incident to passing the arm through a hole, as heretofore.

Having thus described my invention, the following is what I claim as new and desire 75 to secure by Letters Patent:

1. As a new article of manufacture, a flat finished sample profile of a garment, showing quality of material, style of cut, sewing and trimmings, and having a curved recess or cut-away, *a*, for inserting the arm edgewise of the profile, as and for the purpose set forth.

2. The flat finished sample profile of a garment, having a curved recess or cut-away and shoulder and side projections, *b c*, unattached, 85 to inclose the arm, substantially as described and shown.

HENRY LEISER.
